TYPEWRITING MACHINE

Burnham C. Stickney, Hillside, N. J., assignor to
 Underwood Elliott Fisher Company, New York,
 N. Y., a corporation of Delaware

Application October 21, 1933, Serial No. 694,585

38 Claims. (Cl. 197—131)

This invention relates to manifolding work-sheets that are separately collated with plies of carbon-webbing, the latter usually supplied upon spools mountable upon the typewriting machine.

5 An object is to simplify the construction and operation of the machine, and to reduce the cost, and especially to produce a device readily applicable to typewriting machines of standard construction, as, for example, the Underwood. The present invention is preferably an attachment, which may be mounted upon existing machines. The usual platen does not have to be swung up from normal printing position at the carbon-handling operation, as heretofore.

10 In the preferred manner of practicing the present improvements, a collating-board may be detachably mounted upon the usual standard paper-carriage, to extend backwardly from the delivery side of the platen. A front sheet-gage is dropped into position upon the platen. The work-sheets lie face up and are separately gaged by their bottom edges. Leaves of carbon-web are laid upon the work-sheets; the carbon-webs being preferably rolled upon a spool which is 15 journaled under the collating-table so that a loop hangs between the spool and the rear edge of the collating-table; the carbons being clipped against the rear edge of the table during the collating operation.

20 After the sheets are collated, an open sheet-clip, which is mounted upon the platen, is closed to hold the forward edges of the sheets against the platen. Then the gage is swung up out of the way. The platen may then be rotated backwardly (preferably by means of a platen-sweep), and by the aid of the clip the sheets are rolled 25 downwardly and rearwardly under the platen. During this part of the operation, the usual platen-rolls are cast off.

25 Then the clip releases the sheets, and is maintained in idle condition at a location between the platen and the front edge of the collating-board, but below the level of the board. The clip remains at this place during the completion of the drawing of the sheets into the machine, and during the subsequent typing of the sheets.

30 Before the clip is released from the platen, as aforesaid, the feed-rolls are restored, to hold the sheets against the platen.

35 The platen-sweep, which may be connected by movement-multiplying gearing to the platen, may rotate the platen backwardly through two or three revolutions, and may be arrested by a settable stop in position to begin the typing of the 40 first line on the work-sheet.

The typing of the sheet then proceeds line by line; the carbon-web hanging in a loop under the rear portion of the collating-board.

When the typing of the page is completed, 5 the carbon-leaves are again clipped against the rear of the collating-board, whereupon the work-sheets are all grasped by their lower edges and dislodged from the carbons and pulled out of the machine.

10 Then the platen-clip is advanced from its retirement to a temporary open position over the platen. Then the gage is swung down upon the platen just in rear of said clip, and the loading of the sheets with carbons proceeds as before.

15 Said gage consists of a series of teeth, and the clip has teeth which may pass between the gage-teeth, so that the clip may secure the sheets against the platen while they remain set against the gage. The clip is thrown down upon the sheets, and then the gage is lifted, and the 20 platen-sweep operated as before.

25 When the carbon-leaves become worn, fresh lengths of carbon-web may be pulled forwardly from the spool or spools and laid down upon the work-table, and then a knife may be swung forwardly from an idle position and placed upon the carbon-webs, to serve as a tear-off knife for the waste carbon-leaves. Then the knife may be 30 swung to an idle position back of the collating-board.

35 The invention is inexpensively made and readily attached to the carriage of an Underwood machine, without necessitating substantial alteration of construction or operation of the machine or of the carriage. The changes are immaterial, and the new parts operated by the platen may be readily attached after removing the platen from the machine whereupon the platen and its new attachments may be replaced. The invention employs only a few parts, which are all inexpensive.

40 The accompanying drawings or diagrams are principally side elevations, and successive stages are illustrated in the relation of the sheets and the carbons, first interleaving the sheets, then 45 carrying them forwardly and downwardly around the platen preparatory to typing the same line by line, and finally withdrawing the sheets from the carbon-webs, the latter being retained in the machine.

50 Other features and advantages will hereinafter appear.

In the accompanying drawings,

55 Figure 1 shows the front sheet-gage about midway between its normal and working positions,

where it may stand while the typed work-sheets are dislodged and withdrawn.

From the Figure 1 position, the gage is swung down to the platen, as shown in Figure 2, this figure showing the first work-sheet as overlying a carbon which has been placed upon the collating-table. The sheet-clip is shown cast off from the platen.

Figure 3 is a plan of the revoluble platen and 10 the sheet-clip, the latter being hinged upon a bail which is hinged upon the platen-hubs.

Figure 4 shows the completion of the collation of the sheets and carbons against the front gage.

Figure 5 shows the clip as having been thrown 15 against the platen to clamp the sheets thereto while they still remain set against the front gage. From this position, the front gage is thrown up to the dotted-line clear position as seen at Figure 4, where it stands idle during the introduction, 20 typing and withdrawal of the work-sheets.

Figure 6 is a perspective showing the sheets clipped as at Figure 5, and showing the gage swung up from the platen.

Figure 7 shows a plan of the carbon-supply roll. 25 Figure 8 corresponds mainly with Figure 6, and shows the carbon-plies released preparatory to rotation of the platen and the collated sheets (the carbons having been automatically clipped at their rear portions for the sheet-collating operation).

Figure 9 shows the clipped sheets as having been carried around the front and bottom of the platen, from which the feed-rolls stand released.

Figure 10 shows the clip as having passed by the 35 feed-rolls, and the latter as having been restored against the platen. This is preparatory to the automatic release of the sheet-clip.

Figure 11 shows the clip released from the platen and occupying a retired position near the 40 upper rear part of the platen, beneath the incoming work-sheets, and forwardly of the collating-table.

Figure 12 shows a still later stage, in which the work-sheets have been retracted far enough to 45 type the first line thereon.

Figure 13 shows the typing of the work-sheets as having been completed. The sheets have advanced line by line past the bottom feed-rolls, and are ready to be grasped as seen at Figure 1, 50 and withdrawn from the carbon-plies. The latter are clipped against the rear edge of the collating-table. This clip has stood idly in the Figure 13 position, since its automatic release shown at Figure 11, and throughout the typing 55 of the page.

Figure 14 is a plan showing the rear end of the collating-table which has adjustable side-gages, or is adjustable in width. This figure also shows the carbon-clip in open position.

60 Figure 15 is a side elevation seen from the left side of the machine, showing a portion of the typewriter-carriage with the sweep-mechanism for rotating the platen backwardly to feed the collated sheets into the machine. This figure 65 also shows the means for automatically throwing out the line-space spring-detent during such rearward rotation of the platen.

70 Work-sheets 20 are collated upon a table 21, extending rearwardly from the top or delivery side of the revoluble platen 22 of an Underwood typewriter. The table 21 may be supported upon a cross-bar 23 of a bracket having side plates 24 secured by screws 25 to the typewriter-carriage 26, the latter running along a fixed track 75 27. The collating-table 21 inclines downwardly

and forwardly towards the delivery side of the platen, but may be spaced considerably therefrom. The table has side guides 28 for the work-sheets, and is preferably made in opposite width-wise sections, as seen at 21^a, 21^b, Figure 6, adjustable towards and away from each other, and secured by screws 29. The table may have rear sight-openings 30 to expose a carbon-supply spool 31 beneath the table, said spool being mounted upon an axle 32, journaled in side arms 33 formed upon the bracket 24. The spool may carry one or a plurality of plies of carbon 34 which may drop from the front side of the spool and hang in a loop running to the rear end of the collating-board 21. Thus the weight of spool 15 and its carbon-web is brought nearer the carriage-guiding track 27, thus conducing to smooth and rapid operation of the heavy carriage and platen.

Before collating the sheets, a front sheet-gage 20 35 may be swung downwardly and forwardly from its normal upstanding idle position, at Figure 8, to rest upon the top of the platen 22. This gage 35 may be in the form of a bar which is seen at Figure 6 extending the length of the platen and supported upon a pair of side arms 36, which are hinged upon a rock-shaft 37 that is journaled upon the ends 38 of the usual frame in which the platen-axle 39 is journaled. Said gage-shaft 37 may be journaled in a pair of plates 30 40 that are bent down from a pair of top plates 41 secured by screws 42 upon the platen-frame ends 38. The gage is pressed against the platen by a double-acting spring 43; the latter serving also to detain the gage in its upstanding idle 35 position, Figure 8, where it is held against its stop-pin 40^a. The gage having been swung down upon the platen, the work-sheets are collated one by one upon the table 21. After depositing the first work-sheet, a carbon-leaf 34 is swung down 40 thereon; and after depositing the second work-sheet, another carbon-leaf is swung down, and so on.

The carbon-leaves at this time are held by a 45 clip 44 against the rear beaded end 45 of the collating-table 21, Figure 4. This clip is mounted upon a rock-shaft 46 at the rear of the table, Figure 8, and is provided with a closing spring 47. However, the clip is normally held open by a pin 48, which bears against the end of an operating rod 49, the latter being pivoted at its rear end at 50 to an arm 51 extending down from the rock-shaft 46. The forward end of the rod 49 is supported and guided by a pin 24^a fixed to the bracket 24 and extending through a slot 52 in the 55 rod 49. The aforesaid spring 43 is strong enough to hold the clip open when the gage 35 is in idle position, Figure 8.

Said pin 48 is provided upon the left-hand arm 36, and the rod 49 is provided with a finger-piece 53, whereby the clip 44 may be thrown off at will.

The forward ends of the gaged sheets overlie the platen in position for holding them to the platen by means of a clip 54, which, during the 65 collating operation, occupies an idle upstanding position in front of the gage, as at Figure 2. It may be observed that, during the operation of typing these sheets, said clip occupies an idle position seen at Figures 11, 12 and 13, below the 70 path of the work-sheets, between the top of the platen and the front edge of the collating-table 21; but, when swinging downwardly and forwardly the front gage-bar 35 to working position, said open clip 54 is brought forwardly above the platen 75

to a temporary idle position, seen at Figure 4, preparatory to being swung down upon the assembled work-sheets. The clip swings from open to closed position upon a pair of side arms 56, 5 formed upon the clip and pivoted at 55 to a pair of plates 57. Said clip and its side arms form a bail which in this manner is hinged at 55 to a mount, which is also in the form of a bail, its side arms or plates 57 having a connecting bar 58 10 which extends from end to end of the platen; the bail-mount 57, 58 is pivoted upon the hubs 59 of the usual platen-heads between the platen-frame ends 38, permitting rotation of the platen independently of the clip. The clip-bail and the 15 mount swing as a unit around the platen-hubs 59 from idle position at Figures 11 to 13, to temporary forward position at Figure 4.

The clip swings down upon the sheets while their front edges remain in contact with gage 35. 20 To reach its working position, the clip must pass the gage, and for this purpose the gage is made in the form of a series of separated teeth 60, as at Figure 6, and the clip is likewise made of a series of separated teeth 61, said teeth 61 swinging 25 through the spaces between the gage-teeth 60, and dropping upon the work, as at Figure 5, preparatory to backward rotation of the platen for drawing the work downwardly around the front of the platen and rearwardly under the same 30 and upwardly along the paper-shelf 62 which usually forms part of said platen-frame.

The usual front and rear bottom feed-rolls 63, 64 are cast off by the gage-bail 35 when the gage is swung down to the working position, Figure 4. 35 Such release of the rolls is effected by link 65, whose upper end is pivoted at 66 to a short arm 67 formed upon one of the bail-arms 36. The lower end of this link connects to a pivot-pin 68 provided upon arms 69 formed upon a rock-shaft 40 70 having cutaways forming cams 71. These cams usually operate between arms 72 of bell-crank which carry the rolls 63, 64, and separate the arms and lock the rolls in cast-off positions, as at Figure 4, where they stand during the early 45 portion of the introductory rotation of the platen, as long as the sheet-clip 54 remains in use. The lower end of said link is slotted longitudinally as at 73 to permit manipulation at any time of the usual roll-releasing link 74 and its key-lever 75, 50 seen at Figure 9.

The described rotation of the clip-unit may be effected by means of a ratchet-wheel 76 that is fixed to the platen and is engageable by a drive-pawl 77, which, during the typing operation, stands 55 released from the ratchet-wheel, as seen at Figure 4. This drive-pawl is held out by means of a pin 78 that projects from a side arm 56 of the clip-bail, as seen at Figure 4; but, when the operator throws the clip rearwardly and down to working position, the pawl 77 is permitted to be 60 drawn into engagement with the ratchet 76 by means of a spring 79. This engagement is maintained so long as the clip remains closed.

The clip-bail is held in both open and closed 65 positions by means of a double-acting spring 80, which is pivoted at 81 to the mount-arm 57, the other end of the spring being pivotally connected to the side arm 56 of the clip.

Thus the pawl is automatically moved into engagement with the ratchet-wheel, so that backward rotation of the platen will drive the clip-unit bodily around with the platen; neither the pawl 70 nor the clip being released until after the work-sheets are caught by the feed-rolls 63, 64, as now 75 to be described.

As the closed clip 54 passes by the bottom rolls 63, 64, Figure 9, a cam 81^a (which is formed upon one of the end plates 57 of the clip-mount, and which therefore is being driven by the pawl 77) engages a pin 81^b that projects from the key-link 5 14 of the feed-roll mechanism, and forces down said link, thereby permitting the usual springs 81^d to restore the rolls to the platen, as at Figure 10. The rolls thereafter co-operate in the usual way with the platen, whereby the sheets continue to be 10 drawn into the machine; and subsequently they are line-spaced forwardly by the aid of the rolls and the platen in the usual way.

The platen-wheel 76 no longer needs to drive 15 the clip-mount around, and the mount may therefore be released from said wheel, the clip being first automatically opened.

It has been seen that the work-sheets have been drawn in past the rear feed-roll 64, and since the clip has nothing further to do, as at Figure 9, 20 there is utilized a fixed cam-edge 82 that is formed upon a plate 83, Figures 9 and 10, secured to the right-hand platen-frame end 38, Figure 6. This plate 83 is bent down from the right-hand top plate 41. Cam 82 is in the path of a pin 87 25 that projects from one of the side arms 56 of the clip-bail, Figures 6 and 9. When the pin 87 is intercepted by said cam during the further rotation of the platen, the clip-bail is gradually 30 swung to its open position, where it is held by the double-acting spring 80, Figure 11.

It being no longer necessary for the pawl 77 to drive the clip-unit, it is automatically disengaged from the ratchet-wheel 76. For effecting this disengagement, pin 78 is brought into use. During the swinging of the clip-unit outwardly from the platen, said pin engages the underside of the pawl, and lifts it out of the notch in the ratchet-wheel.

At this time the clip occupies a normal idle 40 position between the intake and delivery sides of the platen, or just beneath the work-sheets, the clip nearly bridging the space between the platen and the forward end of the collating-table 21, as at Figures 11-13. 45

The platen continues to rotate backwardly to 50 retract the collated sheets until they reach position for starting to type.

During the typing of the page line by line, the ratchet-wheel 76 rotates idly with the platen; 50 while the sheet-clipping unit 54, 58 remains stationary in idle position, as seen at Figure 13, and the gage 35 remains in its elevated idle position.

At the time of the beginning of the typing, the position of parts is seen at Figure 12, the rear 55 ends of the collated sheets being deflected downwardly by a deflector 88 away from the carbon-spool 31.

The idle clip-unit, Figures 11, 12, is held stationary by means of a detent in the form of a 60 spring-pressed hook 89, which is pivoted at 90 upon one of the gage-arms 36, this hook 89 having a spring 90^a and being provided with a notch which engages pin 91 of the clip-mount 57.

The hook 89 is pivoted to the gage-bail 35, 65 thereby enabling the gage-bail to rotate the clip-unit from permanent idle position, Figure 13, to its forward temporary idle position, Figure 4, in front of the gage 35, where it is still out of the way while the sheets are being collated, but is 70 positioned to swing backwardly and down, so as to clip the collated sheets to the platen, Figure 6.

When the clip-mount 57 reaches its forward position at Figure 4, it is stopped by an elbow 92, which extends down from a side arm 36 of 75

the gage-bail 35, see Figure 4. Said elbow 92 is in the path of pin 91, and is encountered thereby, and further forward rotation of the clip-unit is prevented. The clip-unit is therefore locked by 5 89 and 92 in the Figure 4 position. Owing to the lengthening of elbow 92, the top gage 35 may be swung up without relinquishing control of the clip-mount. This control is maintained until the hook 89 cams itself free from pin 91, by means 10 of cam 92^a, whereby the clip-unit is freed from the hook and the elbow concomitantly, and is ready to be driven around by pawl 77.

During the typing of the page, the collated sheets feed forwardly and up around the platen 15 and back over the table 21; the carbons dropping to form a loop below the carbon-spool.

At the conclusion of the typing of the page, the operator may pull forward the gage-bail with its pin 48, thereby permitting the link-spring 47, 20 Figure 4, to close the clip 44 to clip the carbon-webs to the rear end of the table 21, Figure 1.

At this time the operator may grasp the forward ends of the work-sheets 20, to dislodge them from the carbons and pull them out of the machine. 25

He may then press down the gage from the intermediate Figure 1 position to the position at Figure 2, to swing the clip-unit forwardly by means of the hook 89 to the temporary forward 30 position at Figure 2. The gage is brought down to the top of the platen, preparatory to collating a fresh set of work-sheets in the manner already explained.

There may be provided a platen-sweep mechanism, Figures 4 and 15, for rotating the platen backwardly to draw the collated sheets around the platen as described.

The platen-sweep may have capacity for three platen revolutions to bring long sheets from the 40 position at Figures 4 and 6 to that at Figure 12 at a single stroke of the platen-sweep handle 93. This platen-sweep mechanism may be adapted from Waldheim Patent No. 1,578,941, of March 30, 1926; the same having a normally disengaged 45 pawl 94, which, by means of handle 93, the operator presses down into a notch in the ratchet-wheel 95, having a pitch corresponding to the line-spacing of the platen. By means of this ratchet-wheel, a large gear 96 is caused to rotate 50 a driving pinion 97 fixed upon the platen-axle. The extent of platen rotation depends upon the setting of a stop 98, for which there are provided location-holes 99.

The handle, ratchet-wheel and gear may be 55 mounted upon a vertical bracket-plate 100, which may be anchored upon the platen-axle 39, and may also have a link-anchorage 101 secured to the platen-frame end 38.

The platen has the usual line-spacing mechanism, including ratchet-wheel 102 with its spring-detent roll 103. To avoid the noise of the detent, the latter may be automatically thrown out by a cam 104, which is adapted from Kurowski Patent No. 1,141,558, of June 1, 1915. Said cam 104 is 60 formed upon the end of a lever 105, having at its opposite end a roll 106 which follows a cam 107 which may be connected to the handle 93.

The carbon-roll 31 may be held steady by a spring-washer 108, Figure 6, pressed lightly 65 against a collar 109 fixed upon the spool or shaft 32, and permitting one or more plies of carbon to be drawn off the spool to form fresh leaves.

When a length of fresh carbon has been drawn 70 from the spool, a knife 111 may be swung into 75 the carbon-severing position seen in dotted lines

at Figure 4. This knife 111 is carried by a pair of bail-arms 112, hinged at 113 to opposite arms 114 extending up from the bracket-plates 33. The arm may normally rest upon rear bosses 115, in which are journaled the ends of clip-shaft 46. 5 When in this position, shown in full lines at Figure 4, the knife-bail is back out of the way, leaving an unobstructed space for the manipulation of the work-sheets and carbon-leaves; while the knife may be readily swung forward about the hinge 113 to the dotted-line severing position at the front of table 21. The side gages 28 of the table lie between the knife-bail arms 112, and said gages, near their forward ends, have cut-aways 116 into which the knife-blade 111 may drop upon the carbon-leaves, to hold them down upon the table as the worn-out leaves are torn off.

Variations may be resorted to within the scope of the invention, and portions of the improvements may be used without others.

Having thus described my invention, I claim:

1. In a typewriting machine, the combination with a revoluble platen, of a collating-table having a side gage and extending rearwardly from the delivery side of the platen, a front sheet-gage movable into and out of effective position upon the upper part of the platen; a supply of carbon-web mounted adjacent the collating-table, a sheet-clip carried by the platen and closable upon the forward edges of the gaged sheets, means to rotate the platen backwardly, carrying the clip and the interleaved work-sheets, feed-rolls running upon the platen, means for casting off said feed-rolls, means effective after the clip has 35 passed the rolls to restore said rolls upon the platen, and means for automatically releasing the clip and maintaining it in idle condition below the sheets at the delivery side of the platen, the sheets being typed and advanced over said table 40 and dislodged from the carbons and withdrawn from the machine, the platen-clip being movable forwardly from its retired idle position to a temporary open position forward of the front gage, preparatory to bringing the gage down upon the 45 platen for a repeated series of operations.

2. In a typewriting machine, the combination with a revoluble platen, of a collating-table having a side gage and extending rearwardly from the delivery side of the platen, a front sheet-gage 50 movable into and out of effective position upon the upper part of the platen; a supply of carbon-web mounted adjacent the collating-table, and a sheet-clip carried by the platen and closable upon the forward edges of the gaged sheets, said gage having a series of teeth, and said clip also having 55 teeth to project between the gage-teeth, the clip securing the sheets against the platen while they remain set against the gage, and said clip being mounted upon the platen and occupying an idle 60 position below the work-sheets at the delivery side of the platen during the typing of the sheets.

3. In a typewriting machine, the combination with a revoluble platen, of a collating-table having a side gage and extending rearwardly from the delivery side of the platen, a front sheet-gage 65 movable into and out of effective position upon the upper part of the platen; a supply of carbon-web mounted adjacent the collating-table, a sheet-clip carried by the platen and closable upon the forward edges of the gaged sheets, means to rotate the platen backwardly, carrying the clip and the interleaved work-sheets, feed-rolls running upon the platen, means for casting off said feed-rolls, means effective after the clip 70 75

has passed the rolls to restore said rolls upon the platen, means for automatically releasing the clip and maintaining it in idle condition below the delivery side of the platen, a clip being provided to hold the carbon-leaves at the rear of the paper-table during the withdrawal of the work-sheets and the collation of fresh work-sheets, and means extending forwardly from said carbon-clip to operate the same.

10 4. In a typewriting machine, the combination with a revoluble platen, of an intercalating-table upon which pre-cut work-sheets and carbon-web are assembled, said table having a side gage and extending rearwardly from the delivery side of the platen, a front sheet-gage for pre-cut work-sheets movable into and out of effective position upon the upper part of the platen; a supply of carbon-web mounted adjacent the intercalating-table, a sheet-clip for pre-cut sheets 15 carried by the platen and closable upon the forward edges of the gaged pre-cut sheets, a movement-multiplying platen-sweep connected to rotate the platen backwardly to draw the pre-cut sheets to typing positions, and a settable stop for said platen-sweep to arrest the platen in position to begin the typing of the first line upon the pre-cut work-sheet.

5. In a typewriting machine, the combination with a revoluble platen, of a collating-table having a side gage and extending rearwardly from the delivery side of the platen, a front sheet-gage movable into and ~~out of~~ effective position upon the upper part of the platen; a supply of carbon-web mounted adjacent the collating-table, 20 and a sheet-clip carried by the platen and closable upon the forward edges of the gaged sheets, the carbon-web hanging in a loop under the rear of the collating-table, said carbon-web supply being mounted under said collating-table between the front and rear ends thereof.

40 6. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, and means for releasing the clip and holding it in stationary idle condition clear of the sheets, the platen-clip being movable forwardly over the platen preparatory to repeating the recited operations.

55 7. Machine constructed according to claim 6, in which the front sheet-gage is in the form of a bar extending the length of the platen, and having hinged arms and mechanically held in lowered or raised position.

80 8. Machine constructed according to claim 6, means being provided for connecting said sheet-gage to said clip for bringing the latter to a point forwardly of the gage when the latter is brought down upon the platen.

35 9. The combination of means, including a table, for intercalating work-sheets with plies of carbon-web, a revoluble platen at the front of said table and provided with hub-portions, a sheet-clip having side arms forming a bail, and a mount for said bail, said mount including a bar extending the length of the platen and having arms which are hinged upon the platen-hubs, to permit rotation of the platen relatively to the sheet-clip; said bail and its mount swinging as a unit around

the platen-hubs backwardly to introduce the sheets, rear end first, into the machine.

10 10. Machine constructed according to claim 6, said clip being closable upon the collated sheets while they remain in contact with the front gage, the gage having teeth, and the clip also having teeth passing between the gage-teeth.

11. Machine constructed according to claim 6, having a ratchet-wheel connected to the platen, a normally released drive-pawl for connecting said sheet-clip to said ratchet-wheel, and means to enable the closing of the clip to engage the pawl with the wheel.

15 12. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding it in stationary idle condition clear of the sheets, the platen-clip being movable forwardly over the platen preparatory to repeating the recited operations, a ratchet-wheel connected to the platen, a normally released drive-pawl for connecting said sheet-clip to said ratchet-wheel, means to enable the closing of the clip to engage the pawl with the wheel, and means for automatically releasing the pawl from the ratchet-wheel.

13. Machine constructed according to claim 12, having means for concomitantly opening the clip, and means for detaining the released clip in idle position clear of the work.

14. Machine constructed according to claim 6, said platen having feed-rolls, means automatically releasing said rolls at the stage of combined gaging and clipping the sheets to the platen, and means for automatically restoring the rolls after the sheet-clip has passed by them.

15. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, said platen having feed-rolls, means automatically releasing said rolls at the stage of combined gaging and clipping the sheets to the platen, means for automatically restoring the rolls after the sheet-clip has passed by them, said roll-releasing means including a link which extends from the clip to a roll-releaser, and also including means for automatically locking the rolls away from the platen, and means for releasing the clip from the platen and holding it in stationary idle condition clear of the sheets, said clip being movable forwardly over the platen preparatory to repeating the recited cycle of operations.

16. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding it in stationary idle condition clear of the sheets, the

- platen-clip being movable forwardly over the platen preparatory to repeating the recited operations, said platen having feed-rolls, means automatically releasing said rolls at the stage of combined gaging and clipping the sheets to the platen, and means for automatically restoring the rolls after the sheet-clip has passed by them, said roll-restoring mechanism including a cam which is rotated by the platen, and a restoring pin project-
5 ing from a part of the feed-roll mechanism.
- 10 17. Machine constructed according to claim 16, said cam being provided upon a mount upon which the platen-clip is hinged, said mount being driven by a pawl and ratchet, and means for releasing the mount from the ratchet and opening the clip concomitantly with the movement of the clip beyond the feed-rolls, and a double-acting spring for said clip.
- 15 18. Machine constructed according to claim 12, having means for concomitantly opening the clip, and means for detaining the released clip in idle position clear of the work, a cam-edge being fixed to the platen-frame in the path of a pin that projects from the clip, to swing the clip to its open position, means for holding the clip open, and means for disengaging the pawl from the ratchet-wheel concomitantly with the opening of the clip, thus bringing the clip to normal idle position clear of the overlying sheets.
- 20 19. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding
25 it in stationary idle condition clear of the sheets, the platen-clip being movable forwardly over the platen preparatory to repeating the recited operations, and a detent for holding said clip in its idle forward position, said detent in the form of a spring-pressed hook which is mounted upon said gage and swings said clip to bring the same forward while the gage is descending upon the platen.
- 30 20. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding
35 it in stationary idle condition clear of the sheets, the platen-clip being movable forwardly over the platen preparatory to repeating the recited operations, and a detent for holding said clip in its idle forward position, said detent in the form of a spring-pressed hook which is mounted upon said gage and swings said clip to bring the same forward while the gage is descending upon the platen.
- 40 21. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding
45 it in stationary idle condition clear of the sheets, the platen-clip being movable forwardly over the platen preparatory to repeating the recited operations, a platen-sweep mechanism having a handle connected by movement-multiplying gearing to the platen to rotate it backwardly, and an adjustable stop co-operating with the platen-sweep mechanism to locate the work-sheet in position to receive the first typing line, a normally disconnected pawl-and-ratchet mechanism being provided between said handle and the gear-train.
- 50 22. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding
55 it in stationary idle condition clear of the sheets, the platen-clip being movable forwardly over the platen preparatory to repeating the recited operations, a platen-sweep mechanism having a handle connected by movement-multiplying gearing to the platen to rotate it backwardly, and an adjustable stop co-operating with the platen-sweep mechanism to locate the work-sheet in position to receive the first typing line, a normally disconnected pawl-and-ratchet mechanism being provided between said handle and the gear-train, and a spring-detent therefor, said platen having a notched line-space wheel, and said platen-sweep mechanism including a cam which automatically releases said line-space detent and holds it released during the rotation of the platen by the handle.
- 60 23. A sheet-collating table detachably mounted upon a typewriter-carriage and extending rearwardly from the delivery side of its revoluble platen, said table inclining downwardly and forwardly towards the platen, and having side guides for the work-sheets, and formed with laterally-adjustable sections, and a carbon-spool mounted under said table between the ends thereof, the carbon-web forming a loop hanging between the spool and the rear end of the table.
- 65 24. In a typewriting machine, the combination with a revoluble platen, of a collating-table extending from the delivery side of the platen, a front sheet-gage movable into and out of effective position upon the upper part of the platen; a sheet-clip carried by the platen and closable upon the forward edges of the gaged sheets preparatory to rotation of the platen backwardly, together with the clip and the interleaved work-sheets, means for releasing the clip and holding
70 it in stationary idle condition clear of the sheets, the platen-clip being movable forwardly over the platen preparatory to repeating the recited operations, a spring-clip for clipping the carbon-webs at the rear of the collating-table, and a finger-piece connected to said clip.
- 75 25. In a typewriting machine, the combination

with a revoluble platen, of a collating-table, a front sheet-gage movable to and from the platen; a spool of carbon-web mounted adjacent the collating-table, a sheet-clip for the platen, 5 the platen being rotatable backwardly, together with the clip and the work-sheets and interleaved carbons, releasable feed-rolls running upon the platen, and automatic roll-restoring means effective after the clip has passed the rolls, the 10 clip being releasable to stand in idle condition clear of the overlying work-sheets.

26. Machine construction according to claim 25 and having a movement-multiplying platen-sweep connected to rotate the platen backwardly 15 to draw the sheets to typing positions, and a settable stop for said platen-sweep.

27. In a typewriting machine, the combination with a revoluble platen, of an intercalating table 20 upon which pre-cut work-sheets and carbon-web are assembled, said table having a side gage and extending rearwardly from the delivery side of the platen, a front sheet-gage movable into and out of effective position upon the upper part of 25 the platen; a supply of carbon-web mounted adjacent the intercalating table, a sheet-clip carried by the platen and closable upon the forward edges of the gaged sheets, and means to rotate the platen backwardly, carrying the clip backward therewith, and the interleaved work-sheets 30 bottom end first to position for beginning to type near the top of the sheets.

28. In a typewriting machine, the combination with a revoluble platen, of an intercalating table 35 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, a sheet-clip carried by the platen and closable upon the forward edges of the gaged sheets, means to rotate the platen backwardly, carrying the clip backward 40 therewith and the interleaved work-sheets bottom end first to position for beginning to type near the top of the sheets, feed-rolls running upon the platen, means for casting off said feed-rolls, means effective after the clip has passed the rolls to restore said rolls upon the platen, and means 45 for automatically releasing the clip after the latter has passed the feed-rolls.

29. In a typewriting machine, the combination with a revoluble platen, of an intercalating table 50 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, and a sheet-clip 55 carried by the platen and closable upon the forward edges of the gaged sheets, said gage having a series of teeth, and said clip also having teeth to project between the gage-teeth, the clip securing the sheets against the platen while they remain set against the gage.

30. In a typewriting machine, the combination with a revoluble platen, of an intercalating table 60 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, a sheet-clip 65

carried by the platen and closable upon the forward edges of the gaged sheets, and means to rotate the platen backwardly, carrying the clip and the interleaved work-sheets, a clip being provided to hold the carbon-leaves at the rear of the 5 intercalating table during the withdrawal of the work-sheets and the intercalation of fresh work-sheets.

31. In a typewriting machine, the combination with a revoluble platen, of an intercalating table 10 upon which pre-cut work-sheets and carbon-web are assembled, said table having a side gage and extending rearwardly from the delivery side of the platen, a front sheet-gage movable into and out of effective position upon the upper part of 15 the platen; a supply of carbon-web mounted adjacent the intercalating table, and a sheet-clip carried by the platen and closable upon the forward edges of the gaged sheets, the carbon-web hanging in a loop under the intercalating table. 20

32. In a typewriting machine, the combination with a revoluble platen, of an intercalating table 25 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, a sheet-clip carried by the platen and closable upon the forward 30 edges of the gaged sheets, and means to rotate the platen backwardly, carrying the clip and the interleaved work-sheets, the front sheet-gage being in the form of a bar extending the length of the platen, and having hinged arms and mechanically held in lowered or raised position. 35

33. In a typewriting machine, the combination with a revoluble platen, of an intercalating table 40 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, and a sheet-clip 45 carried by the platen and closable upon the forward edges of the gaged sheets, said gage having a series of teeth, and said clip also having teeth to project between the gage-teeth, the clip securing the sheets against the platen while they remain set against the gage, means being provided for connecting said sheet-gage to said clip for bringing the latter to a point forwardly of the gage when the latter is brought down upon the platen. 55

34. In a typewriting machine, the combination with a revoluble platen, of an intercalating table 60 upon which pre-cut work-sheets and carbon-web are assembled, said table having a side gage and extending rearwardly from the delivery side of the platen, a front sheet-gage movable into and out of effective position upon the upper part of the platen; a supply of carbon-web mounted adjacent the intercalating table, a sheet-clip carried by the platen and closable upon the forward 65 edges of the gaged sheets, and means to rotate the platen backwardly, carrying the clip and the interleaved work-sheets, said clip being closable upon the intercalated sheets while they remain in contact with the front gage, the gage having teeth, and the clip also having teeth passing between the gage-teeth. 70

35. In a typewriting machine, the combination with a revoluble platen, of an intercalating table 75 upon which pre-cut work-sheets and carbon-web

are assembled, said table having a side gage and extending rearwardly from the delivery side of the platen, a front sheet-gage movable into and out of effective position upon the upper part of the platen; a supply of carbon-web mounted adjacent the intercalating table, a sheet-clip carried by the platen and closable upon the forward edges of the gaged sheets, a ratchet-wheel connected to the platen, a normally released drive-pawl for connecting said sheet-clip to said ratchet-wheel, and means to enable the closing of the clip to engage the pawl with the wheel.

36. In a front-strike typewriting machine, the combination of a revoluble platen, releasable bottom feed-rolls, a clip adjacent the platen and closable upon the bottom of a work-sheet presented thereto preparatory to drawing the work-sheet between the platen and feed-rolls, said clip being revoluble, relatively to the platen, about the platen-axis, and means for interlocking said clip and platen whereby, at rotation of said platen, said clip, gripping the work-sheet, is rotated past the released feed-rolls which are then restored, to grip the work-sheet to the platen, said means being operable, after the clip has passed the feed-rolls, for releasing the clip from the platen for detention in an idle position clear of the work-sheet.

37. In a front-strike typewriting machine, the combination of a revoluble platen, feed-rolls at the bottom of the platen, an intercalating table upon which pre-cut work-sheets and carbon-web are assembled, said table extending rearwardly from the delivery side of the platen, a clip asso-

ciated with the platen and rotatable relatively thereto about the platen-axis, said clip being arranged to grip the bottoms of the work-sheets and carbons, said bottoms overlying the platen by reason of the assembly of said work-sheets and carbons upon said table, and means for releasably interlocking said clip with said platen preparatory to rotation of the latter to draw the work-sheets and interleaved carbons around the front of the platen and past the feed-rolls, said means being operative to release the clip from the platen for detention in a position, free of the work-sheets, after the clip has acted to draw the work-sheets past the feed-rolls.

38. In a front-strike typewriting machine, the combination of a revoluble platen, feed-rolls at the bottom of the platen, an intercalating table upon which pre-cut work-sheets and carbon-web are assembled with the bottoms of the work-sheets and carbons in proximity to the top of the platen, a sheet-gripper associated with the platen and closable upon the bottoms of the work-sheets and carbons, to draw said work-sheets and carbons around the front of the platen and past the feed-rolls by backward rotation of the platen, and means whereby said sheet-gripper is automatically cast off after passing the feed-rolls, for further backward platen rotation, independently of the gripper, to advance the first line of the work-sheets to the printing line, said gripper, when cast off, occupying a position behind the platen and below the course of the work-sheets from the table to the platen.

BURNHAM C. STICKNEY.
